[57] CLAIM

The ornamental design for a table, as shown and described.

DESCRIPTION

FIG. 1 is an isometric view of a table showing our new design;

FIG. 2 is a top plan view thereof;

FIG. 3 is a side elevational view thereof, the opposite side being identical thereto;

FIG. 4 is an end elevational view thereof, the opposite end being identical thereto;

FIG. 5 is a bottom plan view thereof; and,

FIG. 6 is a perspective view, showing the table with the leaves removed for convenience of illustration.

“The broken lines are for environmental purposes only and form no part of the claimed design.”
